UNITED STATES PATENT OFFICE.

LEMUEL MELLETT, OF SOMERVILLE, MASSACHUSETTS, ASSIGNOR OF NINE-SIXTEENTHS TO EDWARD GLINES, OF SOMERVILLE, MASSACHUSETTS, JOSEPH F. FLANAGAN, OF NEWTON, MASSACHUSETTS, AND MILES B. McDONNELL, OF BOSTON, MASSACHUSETTS.

SPINNING-RING.

SPECIFICATION forming part of Letters Patent No. 761,086, dated May 31, 1904.

Application filed May 18, 1903. Serial No. 157,550. (No model.)

To all whom it may concern:

Be it known that I, LEMUEL MELLETT, a citizen of the United States, residing in Somerville, in the county of Middlesex and State of Massachusetts, have invented an Improvement in Spinning-Rings, of which the following description, in connection with the accompanying drawings, is a specification, like letters on the drawings representing like parts.

10 This invention relates to a novel ring for spinning and twisting machines, and has for its object to provide a ring with which the speed of the traveler may be greatly increased. For this purpose I employ a ring of non-magnetic material, preferably glass, upon which the traveler, of iron or steel, is mounted to revolve thereon, and a magnetic ring-holder which serves to maintain the traveler in a practically fixed position with relation to the 15 ring and out of contact therewith as the said traveler is revolved about the ring by the yarn being wound upon the bobbin or cop. These 20 and other features of this invention will be pointed out in the claims at the end of this 25 specification.

Figure 1 is an elevation of a sufficient portion of a spinning frame or machine provided with a ring embodying this invention to enable it to be understood; Fig. 2, a plan view, 30 on an enlarged scale, of the ring shown in Fig. 1; and Fig. 3, a section on the line 3 3, Fig. 2.

Referring to Fig. 1, *a* represents the frame, *b* the ring-rail, *c* the guide or wire board, 35 *d* the spindle, *e* the whirl, and *f* the bobbin, of a spinning-machine which may be of any suitable or usual construction.

In accordance with this invention the ring-rail *b* supports a magnetic ring-holder, which 40 may be made as herein shown, and consists of an annular steel ring *g*, provided with pole-pieces *h* *i*, which form an annular groove *j* for the reception of an annular ring *k*, of non-

magnetic material and preferably glass, the said ring being substantially T-shaped in 45 cross-section. The head of the ring *k* is engaged by a steel or iron traveler *m*, through which the yarn *l* passes to the bobbin *f* in the usual manner. In the present instance the ring *k* is represented as secured to the holder 50 by cement *n* or other suitable material. The traveler fits the ring loosely, so as to have a free movement around the same, and as the said traveler is moved around the ring in the operation of the machine, and especially when 55 moving at great speed, it is held out of contact with the ring by the attraction of the magnetic ring-holder, which resists the tendency of the yarn to move the traveler laterally into frictional engagement with the ring, 60 thereby enabling the traveler to be revolved at a speed largely in excess of that now obtained in spinning-machines as now constructed and known to me.

The non-magnetic ring may be provided 65 with a centrally-raised portion or bead *o*, which serves to hold the traveler out of contact with the magnet *g* when at rest.

The magnetic ring-holder *g* may be a permanent magnet, as herein represented, or it 70 may be electromagnetic.

I claim—

1. The combination with a non-magnetic ring, of a magnetic holder therefor, and a traveler mounted on said ring and responsive 75 to the attractive influence of the magnetic holder, substantially as described.

2. The combination with a non-magnetic ring, of a traveler mounted to revolve thereon, and a magnet to keep the said traveler out of 80 contact with the ring while in operation, substantially as described.

3. In a machine of the character described, a revolute traveler and an annular magnet co-operating with said traveler to resist centrifugal action and thereby maintain said 85

traveler in a circular path as it is revolved, substantially as described.

4. The combination with a non-magnetic ring, of a traveler mounted to revolve thereon, and a magnet acting to resist the centrifugal action of the thread upon the traveler, substantially as described.

In testimony whereof I have signed my name to this specification in the presence of two subscribing witnesses.

LEMUEL MELLETT.
